UNITED STATES PATENT OFFICE.

JOSEPH BRUNO, OF HAVERHILL, MASSACHUSETTS.

DESIGN FOR A BLANK FOR SHOE-UPPERS.

SPECIFICATION forming part of Design No. 35,397, dated December 3, 1901.

Application filed October 31, 1901. Serial No. 80,699. Term of patent 7 years.

To all whom it may concern:

Be it known that I, JOSEPH BRUNO, a subject of the King of Italy, and a resident of Haverhill, in the county of Essex and State of Massachusetts, have invented and produced a new and original Design for a Blank for Shoe-Uppers, of which the following is a full, clear, and exact description.

Reference is to be had to the accompanying drawing, forming a part of this specification, in which the figure is a plan view of a blank for shoe-uppers, showing my design.

The design in its entirety consists of the front A, appearing with the side flaps B B' and the tongues CC, ranging one alongside the other from the inner edge of the body A rearward and terminating in the angular arms D D, extending beyond the rear edges of the flaps B B', one of the said arms terminating

in a slightly-curved angular arm E, extending along the outer edge of the adjacent flap B', the latter, as well as the other flap B, appearing at their inner edges with ornamental branches F.

The leading feature of the design consists of the body appearing with the side flaps, the tongues, and the angular arms.

Having described my invention, I claim as new and desire to secure by Letters Patent—

The design for a blank for shoe-uppers, as herein shown and described.

In testimony whereof I have signed my name to this specification in the presence of two subscribing witnesses.

JOSEPH BRUNO.
